Inventor.

By his Attorneys Soule & Co.

UNITED STATES PATENT OFFICE.

WATSON S. LENNON, OF HARDINSBURG, KENTUCKY.

WIRE-SPLICING TOOL.

SPECIFICATION forming part of Letters Patent No. 407,782, dated July 30, 1889.

Application filed May 20, 1889. Serial No. 311,383. (No model.)

To all whom it may concern:

Be it known that I, WATSON S. LENNON, a citizen of the United States, residing at Hardinsburg, in the county of Breckenridge and

5 State of Kentucky, have invented certain new and useful Improvements in Wire-Splicing Tools; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention is an improvement in wire-splicing tools; and my said invention consists of a novel form of tool for connecting the ends of wire fencing, telegraph and other wires, as and for the purposes as will be 20 hereinafter more fully explained, and form the subject-matter of the annexed claims.

25 The object of this invention is to provide a simple and convenient implement whereby the operation of making connection of the 30 ends of wire may be quickly and securely effected; and to this end I proceed as follows, reference being had to the accompanying drawings for a better understanding of the details of construction and operation of the 35 parts, and in which drawings—

Figure 1 is a view in side elevation, and Fig. 2 a plan view, of a wire-splicing tool constructed according to my invention. Fig. 3 is a sectional elevation of the same, and Fig. 35 4 is a view of the wire as spliced.

The tool is composed of a body or main 40 jaw A, having a handle A', a pivoted jaw B, and locking-latch C. The jaw B is pivoted at b within the part A, and beneath the outer 45 end of this jaw B is arranged a spring D, whereby said jaw is held in contact with the jaw A. One end of the jaw B is beveled, as at b', to facilitate the entrance between the jaws of the wire to be spliced, and at this end of said jaw B are formed grooves b², into which said wire is placed.

C is a latch or spring-bolt that is hinged at c to the jaw A and provided with a handle C' and a spring c². This latch C engages

the rear end of the pivoted jaw B, and is so held in engagement with said jaw by the spring c². 50

Opposite the grooves b² of the jaw B in the part A of the implement is a slot a, which slot, in connection with the said grooves b² 55 of the jaw B, forms the recess into which the wires to be spliced are received, and at the bottom of the slot a is a grooved plate b³, adjustable by a set-screw b⁴, whereby the implement is adapted to receive wires of different sizes. 60

E is a grooved stud arranged at the side of the implement adjacent the recess therein that receives the ends of the wire being spliced, the end of one of said wires being 65 bent at a right angle to its length and over the stud E, as in Fig. 2, whereby as the implement is turned around the wires to form the splice said end of the wire is held by the stud in position against the other wire to 70 effect the coupling.

The operation is as follows: Pressure upon the handle C' of the latch releases the bolt C thereof from engagement with the pivoted jaw B, and permits the mouth of said jaw B 75 to open to receive the wire to be spliced. Upon releasing the pressure upon the said handle of the latch, the bolt again engages the outer end of jaw B, which has been returned to its normal position after the passage of the wire into its mouth by the spring D, and holds the same in position upon the wire. The implement is now revolved around the wire and the connection made in the usual manner. 80

This implement may be used in connection with the McIntire connector, if desired. 85

Having thus described my invention, I claim as new and desire to secure by Letters Patent—

1. A wire-splicing tool composed of the 90 handled body A A', with recess a, short jaw B, pivoted to the body A and having a beveled and recessed mouth b' b², spring D, and spring locking-bolt C C', as described, for the purposes specified.

2. In a wire-splicing tool of the nature described, in combination with the handled body A A', with recess a, and short pivoted 95

jaw B, with recess b^2 , of the recessed plate b^3 and set-screw b^4 , as described, for the purposes specified.

3. A tool for splicing wire, composed of a handled body with a recess, short spring-jaw pivoted to said body, a latch engaging said short pivoted jaw, and a stud E, substantially as described, for the purposes specified.

In testimony whereof I affix my signature in presence of two witnesses.

WATSON S. LENNON.
